COMBINED ELECTRICAL AND MECHANICAL
TUNING INSTRUMENT

John H. Teaf, Westmont, N. J., and Albert G. Shafer, Drexel Hill, Pa., assignors, by mesne assignments, to Condenser Development Corporation, Newark, N. J., a corporation of New Jersey

Application November 5, 1938, Serial No. 239,056

17 Claims. (Cl. 74—10)

This invention relates to a unitary tuning structure or instrument for radio work and especially adapted for use in connection with radio receiving sets.

For convenience and to facilitate accurate tuning of broadcast stations, it has been proposed to use a mechanical tuning mechanism having a plurality of manually operated members, each of which corresponds to a personally preselected frequency or station, and which members are operatively connected with a tuning device such as a condenser, so that each desired station may be tuned by any operating manual and that only this manual need be operated to bring in this station.

The mechanical devices so far proposed for this work have been separate mechanisms or adjuncts which must be interconnected with the tuning device, whether it be a condenser or variable inductor. This means that two separate pieces of apparatus must be provided with interconnecting means, all of which must of necessity be handled separately in manufacture, shipping and installation in the radio set.

Furthermore, in these separated prior art structures when, as is usually the case, the tuning instrument is a condenser, these are constructed so that the rotors turn 180° from the position of minimum to maximum capacity, and to get this 180° of movement of the rotors, the mechanical devices heretofore have had to be geared up to the condenser either by direct gearing or the equivalent.

It is the principal object of our invention to provide a unitary structure or instrument which includes the tuning means per se as well as the operating mechanism therefor by which the desired number of stations may be selected by simple mechanical devices incorporated as a part of the unitary structure.

Another object of our invention is to provide a unitary structure or instrument having as a part thereof a tuning device per se such as a condenser which can be moved from the minimum to its maximum capacity by turning the rotor within such limit of angle that the mechanical operating members, one for each frequency, will be capable of moving the rotor of the condenser through its full effective tuning range without any intermediate gearing or the like.

Another object of our invention is to provide manually operable means, one for each desired frequency, which will act directly on the rotor of the tuning condenser or condensers.

Another object of our invention is to provide a

combination unitary instrument which is smaller and more compact than the separate devices now on the market and which is likewise cheaper to manufacture and more efficient in its operation.

These and other objects will be discernible to one skilled in this art from a reading of the specification taken in connection with the annexed drawings, wherein:

Figure 1 is a perspective view on an enlarged scale of the bottom of a two-gang condenser having four manuals incorporated as a part of the unit.

Figure 2 is a part-sectional and part-elevational view taken transversely across the unit shown in Figure 1, with certain parts being removed, but with the rotor in the position of minimum capacity and the condenser being turned to upright position.

Figure 3 is a side elevation of one of the manuals or operating structures shown in Figure 1.

Figure 4 is a view of Figure 3 looking in the direction of the horizontal arrow of Figure 3.

Figure 5 is a view similar to Figure 3, with one side of the clamping lever shown in Figure 3 being broken away.

Figure 6 is a view on the line 6—6 of Figure 5.

Figure 7 is a view similar to Figure 5, but with the setting device shown in dotted lines in a different position.

Figure 8 is a view on the line 8—8 of Figure 3.

Figure 9 is a perspective view of an operating bar.

Figure 10 is a view of a clamping lever which holds the setting device in position on the bar of Figure 9.

Figure 11 is a view of one of the details used in connection with the rotor.

Figure 12 is a modified form of setting device.

Figure 13 is a view similar to Figure 2, but showing the setting device of Figure 12 in position.

Figure 14 shows a modified form of a manual control unit.

Figure 15 is a view on the line 15—15 of Figure 14.

Figure 16 is a partial view similar to Figure 2, but showing a slightly modified form of rotor construction.

Figure 17 is a view similar to Figure 16 but showing a further modified form of rotor and setting device construction.

Figure 18 is a partial view showing a modified form of the end of one of the manual control members.

Figure 19 is a view on the line 18—18 of Figure 18.

Figure 20 is a view on the line 20—20 of Figure 18.

5 Figure 21 is a fragmentary perspective view of the end of the sliding bar shown in Figure 18.

In the different views of the drawings, wherein like numbers correspond to various parts, the unitary structure or instrument as shown in Figure 1 has a frame made up of end plates 1 and 2 held together by frame bars 3 and 4, as well as stator support bars 5 and 6 which, as shown, are swedged into suitable notches in the end plates 1 and 2. The plates 1 and 2 are provided with threaded studs or mounting members 7 for mounting the condenser on a suitable support. As shown in Figure 1, the unit carries two stator groups of plates 8 which are provided with suitable tie bars preferably soldered to terminal plates 9 and 10 carried on their respective insulators 11 and 12 which in turn are fastened in any satisfactory manner, as by rivets 13, to the stator support bars 5 and 6. A shield plate 68 is positioned between the two stators and carries 25 friction end rotor-grounding springs 69.

As shown in Figure 1, each stator is provided with a trimmer plate 14 which is directly connected to the stator bar 6 but insulated from its terminal by a suitable insulator such as a piece 30 of mica 15 and adjustable by a screw 16. Each rotor is composed of a plurality of plates 17 fastened to the shaft 18 in any satisfactory manner such as set forth in Swope Patent 1,620,244, issued March 8, 1927. The rotor shaft 18 is supported between the frame members 1 and 2 in any satisfactory manner as by suitable bearings such as illustrated in Cramer Patent 1,800,719, issued April 14, 1931.

Fastened to the rotor shaft 18, just inside 40 the frame members 1 and 2, are yoke members 19, each yoke being provided with a throat 20 fitting the shaft 18. Extending between the yoke members 19 are engagement means or members 21 for a purpose which will be herein- 45 after described.

Since the manuals or means for operating the tuning element are all alike, a description of one will suffice for all. One of these manuals is illustrated in Figure 3 and associated figures, and 50 is composed of a bar member 22 having one end 23 adapted to slide in suitable slots or orifices in a rear guide plate or bar 24 which is held in place in the frame members 1 and 2 by means of lugs 25 which are engaged by slots in the 55 end of the plate 24 and held in place by any suitable means such as drive pins 26. The front end 27 of the bar 22 is supported in a suitable orifice in the front guide plate 28. The bar 22 has a projection 29 having a hole 30 at its extremity. At the base of the projection 29 the bar is provided with an orifice 31 which opens to the front end of the bar by means of a slot 32. What may be termed the inner surface of the projection 29 is arcuately formed at 33 to 60 provide a seat for a positioning element or setting device 34 which also has a similarly arcuately formed surface 35 to engage the seat 33. The setting device 34 is held in place on the seat 33 by a lever 36 pivoted by a pivot pin 37 passing 65 through the hole 30 in the projection 29. The lever 36 is U or channel-shaped at the point where the section line 8—8 is taken, the lever having two sides connected by a yoke 38 which embraces the setting device 34. The device 34 70 is provided with claws 39 and 40 which limit the 75

arcuate movement of the member 34 on its seat 33, it being understood that the setting device 34 is assembled within the lever 36 before the lever is attached to its pivot 37 carried by the projection 29.

The lower end of the opposite sides of the lever 36 has rectangular-shaped slots 41 there- 5 in. When the lever 36 is in place on the bar 22, the slots 41 are in alignment or cooperative position with the opening 31 in the bar 22, and during assembly operation a polygonally-shaped nut 42 is located transversely of the lever 36 in the slots 41 and in the opening 31 which is provided with an extension 43 for assembling the nut into position, better shown in Figure 6, where- 15 in it is seen that the nut 42 has grooves 44 which receive the edges 45 forming the top and bottom of the opening 31.

Positioned in the slot 32 is a rod 46 which is threaded into the nut 42 as clearly indicated 20 in Figure 5. The rod 46 is held to the end 21 of the bar 22 by a collar 47 which is preferably swedged into place thereon. On the outer end of the rod 46 is mounted, in any satisfactory manner, a push-button 48 preferably having a 25 knurled head 49.

It will be readily understood that when the rod 46 is turned in right-hand direction by the button 48, the nut 42 will be caused to travel toward the button carrying the end of the lever 36 with it, thereby drawing the yoke 38 tightly against the setting device 34 and at the same time forcing the inner end of the rod 46 against the wall 50, thereby securely locking the setting device or positioning element 34 against the seat 33 of the bar 22.

When it is desired to connect or tune in a certain station or frequency with one of the manuals, one of the buttons 48 is rotated to release the setting device 34 and at the same time the 40 button is pushed in, causing the bar 22 to slide inwardly so that the ends 51 and 52 of the setting device 34 will engage the engagement means or bars 21 comprising an integral part of the rotor structure, it being understood that at this time 45 the shaft 18 of the rotor has been turned by a suitable hand-control connected thereto so as to tune in the desired station. Holding the rotor then in this exact tuning position and with the surfaces 51 and 52 both in engagement with their 50 respective bars 21 on the rotor, the member 34 is locked in position in the manner heretofore described so that thereafter, to select this station, all that is required is merely to push in on the button 48. It may be noted in passing 55 that the arcuate seat for the positioning element or setting device 34 has a phantom center of rotation, and is not adjustably movable about a pivot.

On releasing the button 48 the sliding bar 22 60 is returned to normal position by a spring 53 attached at one end to a hole 54 in the bar 22, and at the other end to suitable fastening means in the frame member 28.

Instead of using the yoke member 19, the bars 65 21 may be fastened directly to the rotor plates 17 as shown in Figure 13, or the setting device 34 may be formed with lugs 55 as shown in Figure 12, which may engage the bars 21 as shown in Figure 13, or they may directly engage a plu- 70 rality of rotor plates.

The manuals may take the form as shown in Figures 14 and 15, in which a sliding bar 56 has pivoted thereto a beam 57 slotted at its opposite ends to receive pins 58 positioned in slides 59 and 75

60 which are adapted to contact with the engagement bars 21. The slides 59 and 60 are carried on a suitable support 61 having ledges 62 and 63 for properly supporting the slide members 59 and 60. The push rod 46 is supported by lugs 64 and 65 formed from the bar 56 which is slotted to receive a member 66 that engages the cam surface 67 on the beam 57 when the screw 46 is turned inwardly as shown in Figure 15. Adjustment of the beam 57 is carried out in a similar manner as for the manuals shown in Figure 3.

In Figure 16 the bar members 70 are made out of flat stock formed semi-circular in shape instead of being solid stock as shown in Figure 2; otherwise the construction and operation of the device is the same as in Figure 2. It may be noted, however, that instead of forming the members 70 substantially semi-circular as shown in Figure 16, they may be made channel-shaped with rounded corners, and the ends 52 of the member 34 made more curvilinearly so that the outer faces of the channels are in the same plane and no part of the member 34 passes beyond the plane or within the space bounded by the bar members 70.

Another modification of this same idea is shown in Figure 17, where the bars 71 are flat members and the ends of the member 34 are curvilinearly formed at 72.

In Figures 18 to 21 inclusive, the outer end 27 of the sliding bar member 22 has notches 13 formed therein to receive a transverse plate 74 having a hole therein to act as a guide for the outer end of the rod 46 having a slotted head 75 by which the rod 46 may be adjusted by means of a screw driver after removing a cap 76 which is slidably positioned over the end 27 of the manual bar 22. The end 27 is provided with a lug 77 thrown outwardly from the sides of the bar which prevents the split portions of the bar from changing their relative position, thereby rendering it easy to remove the cap 76 which is grooved as clearly shown in Figure 19 to receive the edges of the bar ends 27. As shown in Figure 18, the cap 76 is shown in actuated position with respect to the panels 78.

If desired, the outer end 27 of the manual 22 may be provided with an adjustable extension, the outer end of which may have a suitable cap similar to 76 so as to allow the combination unit structure to be mounted a distance back to the panel 78 to take care of various thicknesses of panels or changes in location of the unit within 55 the cabinet as required by different radio set manufacturers.

It will be understood that the stator and rotor plates 8 and 17 respectively are formed to give the desired capacity tuning curve and also, they 60 are formed and positioned so that the rotor will move from minimum to maximum capacity position by being turned through an angle of approximately 80 to 90 degrees.

From what has been said, it will be understood that certain of the details may be varied without departing from the spirit of our invention or the scope of the appended claims.

We claim:

1. A unitary structure for the purpose described, including a frame, tuning elements, one of which is movable, for a radio set, carried within the frame, a plurality of manually operable members slidably mounted on the frame and each having an arcuately formed part with the 75 ends thereof adapted to successively engage

spaced points on said movable element to move the same to a predetermined position for the purpose described, said part being bodily shiftable to its operative position.

2. A unitary structure for the purpose described including a frame, at least one stator and rotor mounted within said frame, a plurality of slidable members carried by the frame, each member comprising a bar having a push button for operating it and also having an intermediate projection, a surface of which is arcuately formed, a member pivotally carried on said projection and extending downwardly to the base thereof and across the bar, a part having its ends formed to engage the rotor to turn the same, said part having an arcuately formed surface to fit the arcuately formed surface on said projection, means on said pivoted member to position said part and grip and hold it in adjusted position, and means carried by said bar 20 for moving said pivoted member to permit adjustment of said part and then lock the same in position.

3. A unitary structure for the purpose described including a frame, at least one stator 25 and rotor mounted within said frame, a plurality of slidable members carried by the frame, each member comprising a bar having a push button for operating it and also having an intermediate projection, a surface of which is arcuately formed, a member pivotally carried on said projection and extending downwardly to the base thereof and across the bar and having a U-shaped cross-section which embraces said projection and a section of the bar, a part 35 having its ends formed to engage the rotor to turn the same, said part having an arcuately formed surface to fit the arcuately formed surface on said projection, means on said pivoted member to hold the said part in adjusted position, and means, including a member carrying said push button and rotated thereby independent of the sliding action of the bar, for moving said pivoted member to permit adjustment of said part and then lock the same in position. 45

4. A unitary structure for the purpose described including a frame, at least one stator and rotor mounted within said frame, a plurality of slidable members carried by the frame, each member comprising a bar having a push 50 button for operating it and also having an intermediate projection, a surface of which is arcuately formed, a member pivotally carried on said projection and extending downwardly to the base thereof and across the bar and having a U-shaped cross-section which embraces said projection and a section of the bar, a part having its ends formed to engage the rotor to turn the same, said part having an arcuately formed surface on said projection, means on said pivoted member to hold the said part in adjusted position, said pivoted member having a transverse slot in both arms of the U near the free 55 end thereof, said bar having an opening therein in alignment with the slot in said pivoted member, a nut non-rotatably mounted in said slot and opening, the bar being slotted from said opening to the push button end, a threaded rod positioned in said bar slot and threaded into said nut for the purpose described, the outer end of the rod carrying the button to operate the rod rotatively to adjust said rotor-engaging part, and reciprocatively to move the bar to turn the rotor. 60

5. A unitary structure for the purpose de- 75

scribed including a frame, at least one stator and rotor mounted within said frame, a plurality of manually operable members carried by the frame and each having a part adapted to directly engage the rotor to turn it, said part being arcuately formed and positioned in an arcuately formed seat, means for holding said part in any adjusted position on said seat, said part being bodily slideable in its seat when released and moved for adjustment to match a chosen frequency.

6. A tuning instrument for a radio set including a frame, tuning elements, one of which is movable, carried within the frame, a plurality of movable members also carried by the frame for moving said movable element to a predetermined tuning position, each of the movable members comprising a bar slidably mounted in the frame, the bar having a projection, a lever pivoted to the end of said projection and extending downwardly over the bar, a setting device slidably carried between the lever and the projection and adjustable means interlocking between the end of the lever opposite the pivot and the bar for moving the lever so said device is gripped in an adjusted position, and means for sliding the bar to cause said setting device to engage the movable member to move the same to said predetermined position.

30 7. A tuning instrument for a radio set including a frame, tuning elements, one of which is movable, carried within the frame, a plurality of movable members also carried by the frame for moving said movable element to a predetermined tuning position, each of the movable members comprising a bar slidably mounted in the frame, the bar having a projection, a lever having spaced sides pivoted at one end to the end of the projection and extending downwardly so its sides embrace the projection and bridge the bar, a setting device slidably positioned between the sides of the lever and against the projection with means for holding said device in place while being adjusted, said lever having a transverse slot 45 in the end opposite its pivot, said bar having an opening therein in cooperative relation to the slot in the lever, a nut non-rotatably positioned in the lever slot but longitudinally movable in the bar opening, a rod carried by the bar and threaded into the nut, and means at the outer end of the rod for turning it to cause the nut to move on the threaded end, thereby shifting the lever, causing it to act on said setting device for adjusting and gripping the same, and means also located at the outer end of the rod for sliding the bar to cause said setting device to move the tuning element of the set.

8. Means for positioning a movable tuning element of a radio set to tunably respond to a desired frequency, said means including; a frame, a sliding bar carried by the frame, the bar having a projection, a lever pivoted at one end to the end of the projection, a setting device carried 60 between the lever and the projection on the bar, a shiftable connection between the end of the lever away from the pivot and the bar, means carried by the bar for actuating said connection to adjust said setting device to a position corresponding to a desired frequency, and means for sliding the bar to cause said setting device to engage said tuning element to move it to a position fixed by the setting device.

9. Means for positioning a movable tuning element of a radio set to tunably respond to a de-

sired frequency, said means including; a frame, a sliding bar carried by the frame, the bar having a projection, a channel-shaped lever pivoted at one end to the end of the projection, a setting device carried within the channel of the lever and against the edge of said projection, the lever extending downward over the bar and having a transverse slot therein while the bar has a cooperative opening therein, a nut set in the slot of the lever but movable in the bar opening, a rod carried by the bar and having one end threaded into the nut, and means on the other end of the rod for turning it to cause the nut to travel longitudinally on the threaded end of the rod, thereby moving the lever to free and grip said setting device between the lever and projection for adjusting it to correspond to a desired frequency and fastening it in operative position, and means associated with the bar and rod to slide said bar, thereby causing the setting device to engage the tuning element and move it to tuning position.

10. Means for angularly positioning the rotatable member of a variable condenser of a radio set to a desired frequency, said means including, a frame, a sliding bar carried by the frame, the bar having a projection, a lever pivoted at one end to the end of the projection, the projection having a curved seat portion, a setting device having a curved surface to fit against said curved seat, and spaced surfaces to engage arcuately spaced portions on said rotatable member, the setting device being held in place by said lever, the non-pivotal end of the lever having a shiftable connection between it and the bar, means carried by the bar for actuating said connection to adjust said setting device to a position corresponding to a desired frequency, and means for sliding the bar to cause said setting device to engage and turn the rotatable member to a position fixed by the setting device.

11. In a radio tuning device including in combination, a single frame structure, a variable condenser comprising stator and rotor groups of plates mounted within the frame, the stator and rotor plates being formed and mounted so the rotor plates may be moved from minimum to maximum capacity by turning the rotor through an arc range of ninety degrees or less, engagement parts integral with the rotor, a plurality of adjustable positioning elements adapted to engage said engagement parts, and manually operated members, one for each adjustable element, for supporting its said element on a curved peripheral surface to allow the positioning element to shift bodily on said curved surface about a pivotless phantom center.

12. A tuning instrument for a radio set including a frame, stator and rotor groups of plates mounted within the frame, the rotor having means for being rotatably acted upon, manually operable members supported by the frame, each of said members having an element bodily shiftable for adjustment on an arcuately formed seat about a non-pivotal phantom center and adapted, when moved by its member, to engage said means on the rotor for turning the rotor to a predetermined position.

13. A tuning instrument for a radio set including a frame, stator and rotor groups of plates mounted within the frame, the rotor having means for being rotatably acted upon, manually operable members slidably supported by the frame, each of said members having an arcu-

- ately formed element with means for anchoring the element in a position determined by a chosen rotor setting, said element being bodily shiftable automatically to a chosen position when temporarily released by the anchoring means and the sliding member is operated for bringing the said means on the rotor and said element into engagement, the rotor being held in tuning position for a given frequency.
- 10 14. A tuning instrument for a radio set including a frame, stator and rotor groups of plates mounted within the frame, bars carried by the rotor plates on the outer edges, one on each side of the rotor axis and having their outer surfaces in the same plane, manually operable members supported by the frame, an adjustable element carried by each of said members and adapted, when moved by its member, to engage said outer surfaces of said rotor bars and turn the 15 rotor to a predetermined position.
- 15 15. A tuning instrument for a radio set including a frame, stator and rotor groups of plates mounted within the frame, bars carried by the rotor groups, one on each side of their axes, 20 manually operable members supported by the frame, a pivotless positioning element adjustably carried by each of said members and adapted, when moved by its member, to engage said bars in a plane which is completely exterior to 25 the space between said bars and turn the rotor to a predetermined position.
- 20 16. A tuning instrument for a radio set including a frame, tuning elements, one of which is movable, carried within the frame, a plurality of 30 movable members also carried by the frame for moving said movable element to a predetermined tuning position, each of the movable members comprising a bar slidably mounted in the frame, the bar having a projection, a lever pivoted to the end of said projection and extending 35 downwardly over the bar, a setting device slidably carried between the lever and the projection and 40 adjustable means interlocking between the end of the lever opposite the pivot and the bar for moving the lever so said device is gripped in an adjusted position, said interlocking means including a rod carried by the bar and threaded into a part carried by the non-pivotal end of said lever, the outer end of the bar being divided into two portions between which the rod is positioned, a bearing member on the bar for the outer end of the rod, a lug formed outwardly from the plane of the bar and from said two portions, anchoring them in fixed relation, and a cap slidably mounted on the said two portions of the bar over the head of the rod, lug and rod-bearing member.
- 25 26. A tuning instrument for a radio set includ- 30 ing a frame, tuning elements, one of which is movable, carried within the frame, a plurality of 35 movable members also carried by the frame for moving said movable element to a predetermined tuning position, each of the movable members comprising a bar slidably mounted in the frame, the bar having a projection, a lever pivoted to the end of said projection and extending 40 downwardly over the bar, a setting device slidably carried between the lever and the pro-
- jection and adjustable means interlocking between the end of the lever opposite the pivot and the bar for moving the lever so said device is gripped in an adjusted position, said interlocking means including a nut carried by the lever transversely across the bar and a rod threaded into the nut and extending longitudinally of the bar toward its outer end, a cap removably positioned over the end of the bar concealing the head of the rod, said cap also serving to transmit a pushing force to the bar to slide the same and move the setting device into engagement with said movable element to move it to said predetermined position.
- 30 17. A tuning instrument for a radio set includ- 35 ing a frame, tuning elements, one of which is movable, carried within the frame, a plurality of 40 movable members also carried by the frame for moving said movable element to a predetermined tuning position, each of the movable members comprising a bar slidably mounted in the frame, the bar having a projection, a lever pivoted to the end of said projection and extending downwardly over the bar, a setting device slidably carried between the lever and the projection and 45 adjustable means interlocking between the end of the lever opposite the pivot and the bar for moving the lever so said device is gripped in an adjusted position, said interlocking means including a rod carried by the bar and threaded into a part carried by the non-pivotal end of said lever, the outer end of the bar being divided into two portions between which the rod is positioned, a bearing member on the bar for the outer end of the rod, a lug formed outwardly from the plane of the bar and from said two portions, anchoring them in fixed relation, and a cap slidably mounted on the said two portions of the bar over the head of the rod, lug and rod-bearing member.

JOHN H. TEAF.

ALBERT G. SHAFER.
